UNITED STATES PATENT OFFICE.

JOSEPH M. SHERMAN, OF SEATTLE, WASHINGTON.

AUTOMATIC CUT-OUT.

1,221,232.

Specification of Letters Patent.

Patented Apr. 3, 1917.

Application filed May 1, 1916. Serial No. 94,829.

To all whom it may concern:

Be it known that I, JOSEPH M. SHERMAN, a citizen of the United States, residing at Seattle, in the county of King and State 5 of Washington, have invented a certain new and useful Improvement in Automatic Cut-Outs, of which the following is a specification.

My invention relates to improvements in 10 automatic cut-out devices for electric circuits, and the object of my invention is to provide a cut-out which shall operate automatically to cut-out or "short circuit" a portion of an electric circuit with which it is 15 associated when the continuity of the conductor within such portion is accidentally broken, thus to maintain the integrity of said circuit.

A more particular object of my invention 20 is to provide cut-out devices of a simple form of construction which shall be especially adapted to be associated with an electrical circuit that includes a plurality of electrical translating devices connected in series 25 therein to be operated by a constant current of electricity flowing therethrough, as, for instance, a city street lighting circuit comprising a pole line conductor from which extends a plurality of loops in each of which 30 is connected one or more electric lamps to be operated by a constant current, all of said lamps and all of said loops being connected in series with said pole line conductor, one of said cut-out devices being interposed be- 35 tween each of said loops and said pole line conductor, which cut-out device so connected shall be adapted automatically to operate to short circuit its loop in response to an accidental break in the continuity thereof, there- 40 by to prevent an interruption in the operation of the lamps connected in the other loops.

I accomplish these objects by devices illustrated in the accompanying drawings where 45 in Figure 1 is a diagram showing cut-out devices, embodying one form of my invention, operatively associated with two electric lamps and loops connected with a fragment of a pole line conductor of a street lighting 50 circuit; Fig. 2 is an enlarged view in longitudinal mid-section of one of said cut-out devices; and Fig. 3 is a view showing the same in cross-section on broken line x, x of Fig. 2 as secured to a supporting base.

55 Referring to the drawings, throughout which like reference numerals designate like

parts, two metal wires 4 and 5 are secured in positions parallel with and spaced from each other for the greater portion of their lengths by spaced plates or disks 6 and 7 of 60 material that is a non-conductor of electricity, as porcelain, which disks 6 and 7 are provided each with two correspondingly spaced holes through which project the opposite end portions 8 and 9, and 10 and 11, 65 respectively, of said wires 4 and 5, as shown more clearly in Fig. 2.

Those portions of the wires 4 and 5 which extend between said disks 6 and 7 are each embedded in a separate mass of metal, as 70 masses 12 and 13 respectively, which may melt or fuse at a low temperature, as an alloy of lead and tin, which masses 12 and 13 of metal are each of substantially semi-circular form and of such dimensions in cross-section as will cause their adjacent surfaces to be separated by a space as shown in Figs. 2 and 3.

Surrounding the disks 6 and 7 and all parts associated therewith is an inclosing 80 tube 14 (made of a material that is a non-conductor of electricity) whose inner circular surface engages with and closely fits the peripheries of said disks 6 and 7 as shown in Fig. 2.

85 Each of the opposite end portions of the inclosing tube 14 is covered by a metal cap (as caps 15 and 16) whose hollow cylindrical portion closely fits the outer circumferential surface of said tube 14.

The cap 15 is electrically connected by solder to the end portion 8 of the wire 4, which end portion 8 extends in a staggered course from the disk 6 to and through the central portion of said cap 15, and in a similar manner the cap 16 is connected to the end portion 11 of the wire 5, which end portion 11 extends in a staggered course from the disk 7 to and through the cap 16.

The end portion 9 of the wire 4 that 100 projects through the disk 7 is short and is bent abruptly to a right angle to engage with the outer side of said disk 7; while the end portion 10 of the wire 5 is likewise short and bent to a right angle to engage 105 with the outer side of the disk 6.

As shown in Fig. 2 the respective spaces within the inclosing tube 14 between the cap 15 and the disk 6 and between the cap 16 and the disk 7 are both filled compactly 110 with material that is a non-conductor of electricity, as asbestos or plaster of Paris,

thereby to prevent the wires 4 and 5 from rotatively moving thus to keep the adjacent broad surfaces of the masses 12 and 13 of fusible metal separated from each other.

5 Mounted on a base (like base 17) made of non-conducting material, are two pairs of spring metal clips 18 and 19, of well known form, the pair of clips 18 being disposed on one end portion and the pair of clips 19 being disposed on the other end portion of said base 17 in such manner that they will be adapted to engage with the cylindrical surfaces of the caps 15 and 16 respectively of a tube 14, as indicated in 10 Figs. 1 and 3, thereby releasably to hold said tube 14 in its position on said base 17 and to make a good electrical contact between said clips 18 and the cap 15 and between the clips 19 and the cap 16, thus 15 permitting either of the clips 18 to serve as one electric terminal of the device and permitting either of the clips 19 to serve as the other terminal of such device.

The function and mode of operation of 20 my cut-out as embodied in the structure of Figs. 2 and 3, may be understood by reference to Fig. 1 wherein 20 represents a portion of a street lighting circuit which may include a plurality of electric lamps 25 designed to be operated by a constant current, from which circuit 20 extends a loop comprising conductors 21 and 22 which include two electric lamps 23 and 24 in series therewith, whereby the circuit 20 together with 30 any lamp that may be connected in series therein, is thus connected in series with the conductors 21 and 22 and with lamps 23 and 24.

One of my cut-outs has one of its terminals connected with the conductor 22, while 40 its other terminal is connected to the conductor 21 at points adjacent to the circuit 20, whereby such cut-out may be adapted to operate to short circuit the entire loop comprising the conductors 21 and 22.

Another one of my cut-outs has its terminals connected respectively with the conductors 21 and 22 at points near the terminals of the lamp 23, whereby said lamp 23 50 may be short circuited in response to the operation of said other one of said cut-outs.

A third one of my cut-outs has one of its terminals connected to the conductor 22 at a point adjacent to one terminal of the 55 lamp 24 while the other terminal of said cut-out is connected to said conductor 22 at a point adjacent to the other terminal of said lamp 24, whereby said lamp 24 may be short circuited in response to the operation of said third one of my cut-outs.

The circuit 20 being supplied with a constant electric current by a generator which is adapted to be self regulating to generate a constant current irrespective of changes 65 in the resistance of said circuit 20, it is

manifest that if a break occurs in said circuit 20, or in any loop thereof, then said generator will automatically act enormously to increase the difference in potential between its terminals thereby enormously to increase 70 the voltage to which said circuit 20 will be subjected, and, therefore, if the loop comprising the conductors 21 and 22 be accidentally broken during the operation of the circuit, then the difference in potential between the 75 masses 12 and 13, of fusible metal, in the cut-out adjacent to said circuit 20, will increase to such extent that a current will jump from one of the masses 12 and 13 to the other thereof to form an arc, which arc 80 will immediately melt or fuse such portion of said masses 12 and 13, of fusible metal as will cause such molten portions of such metal to unite and form a conducting bridge between said masses 12 and 13 whereupon 85 such arc will be extinguished and said loop will thus be short circuited or cut-out from said circuit 20 in an obvious manner, and then said generator will automatically adjust itself to generate the required voltage 90 to supply the normal constant current to said circuit 20.

If, however, a break should occur in either 95 of the conductors 21 or 22 between the lamp 23 and the adjacent cut-out, then said adjacent cut-out would operate to short circuit said lamp 23 provided the distance between its masses 12 and 13 be slightly shorter than the distance between the masses 12 and 13 of the cut-out adjacent to the pole line 100 circuit 20; and in like manner if a break should occur in the conductor 22 at a point between the terminals of the lamp 24 and the adjacent cut-out, then said adjacent cut-out would operate to short circuit said lamp 105 24 if the masses 12 and 13 of said cut-out be less widely separated than the masses 12 and 13 of the cut-out adjacent to the pole line 20.

Preferably all the cut-outs associated with 110 the several lamps which are included in a loop connected with a main pole line are alike with respect to the distance between their respective masses 12 and 13, and the cut-out in such loop that is disposed adjacent to the main pole line circuit has its masses 12 and 13 disposed at a slightly greater distance from each other, whereby 115 one of the lamps of such loop might be cut-out without disturbing the operation of the 120 other lamps of such loop.

The advantages of utilizing my cut-out in the manner illustrated and described, will be obvious in view of the fact that the records of one of the largest and best series 125 of street lighting systems in the United States show that ninety five per cent. of the accidental breaks in its several circuits have occurred in loops that extend from the main pole line, and in slack swinging loops lead- 130

ing therefrom to suspended lamps, and such breaks extinguish all lamps of the whole circuit, but if my cut-out be associated with each of such loops, then only the lamp or lamps within the loop wherein the break occurs will be extinguished.

Manifestly, the masses 12 and 13 of fusible metal may be of a different form and be associated with a different form of terminals 10 and be disposed in a different form of inclosing case without departing from the spirit of my invention.

What I claim is:

1. In a cut-out of the class described, the combination with an inclosing case made of material that is a non-conductor of electricity and having end walls of metal, of two plates of electrical insulating material transversely disposed within said inclosing case and spaced from each other, said plates being provided each with two correspondingly spaced holes extending therethrough; two pieces of metal wire disposed to extend between said plates in lines parallel with, and spaced from, each other with their opposite end portions projected through respective ones of the holes of the adjacent one of said plates, one end portion of one

of said wires being extended to and connected with the adjacent one of said end 30 walls and one end portion of the other of said wires being extended to and connected with the other of said end walls; and two separated masses of metal disposed within said inclosing case between said plates, each 35 of said masses being in metallic connection with a different one of said wires; and the metal of said masses being of a character to be fusible at a low temperature.

2. An electric cut-out of the class described which embodies an inclosing case made of non-conducting material and having metal end walls; and two separated masses of metal disposed within said inclosing case, one of said masses being electrically connected with one of said metal end walls while the other of said masses is electrically connected to the other of said end walls, the metal of said masses being fusible 50 at a low temperature.

In witness whereof, I hereunto subscribe my name this 25th day of April A. D. 1916.

JOSEPH M. SHERMAN.
